DAVID C. SASSEMAN, OF RIVER FOREST, ILLINOIS, ASSIGNOR TO F. H. SMITH MANUFACTURING COMPANY, OF CHICAGO, ILLINOIS, A CORPORATION OF ILLINOIS.

RIVET-SETTING MACHINE.

1,116,849.

Specification of Letters Patent.

Patented Nov. 10, 1914.

Application filed October 22, 1913. Serial No. 796,711.

To all whom it may concern:

Be it known that I, DAVID C. SASSEMAN, a citizen of the United States, residing at River Forest, in the county of Cook and 5 State of Illinois, have invented new and useful Improvements in Rivet-Setting Machines, of which the following is a specification, reference being had to the accompanying drawings, forming a part thereof.

10 The purpose of this invention is to provide a rivet setting machine with improved means for holding and guiding the rivets at the instant of driving, and with means for controlling the rate of feed of the rivets 15 from the source of supply to such holding means.

It consists of the features and elements described and shown in the drawings as indicated in the claims.

20 In the drawings: Figure 1 is a side elevation of certain parts of the rivet setting machine, including features which are the subject of this invention. Fig. 2 is a front elevation of the parts shown in Fig. 1. Fig. 25 3 is a detail section of the rivet driving plunger and the rivet holder associated therewith. Fig. 4 is a section taken in a plane at right angles to that of Fig. 3, showing the driving plunger approaching its 30 driving position and incidentally closing the rivet feed tube. Fig. 5 is a section taken similarly to Fig. 3 showing the plunger in final driving position. Fig. 6 is a detail section taken as indicated at line 6—6 on Fig. 1. Fig. 7 is a detail plan view of the feed-controlling escapement taken looking in the direction of the arrows 7—7 on Fig. 1. Fig. 8 is a detail section taken as indicated at line 8—8 on Fig. 7. Fig. 9 is a 40 detail rear elevation of the lower portion of the head, showing certain parts in a different position from Fig. 3. Fig. 10 is an enlarged vertical section of one of the holder jaws.

45 For the sake of simplicity only the parts of the rivet setting machine which are directly concerned with the novel features hereinafter described have been included in the drawing. As illustrated in Figs. 1 and 50 2 these parts comprise a driver, A, mounted for vertical reciprocation in guides, B¹ and B², and operated from its upper end by any convenient linkage indicated at C. The lower end of the driver, A, is made hollow

to receive the rivets one at a time just previous to driving, and the supply tube, D, from which these rivets are fed to the driver is mounted with its lower end in fixed relation to the driver and communicating with the hollow portion thereof, while its upper end is guided at B³, for reciprocation with the driver, A. The supply tube, D, may be filled to its capacity with rivets stacked with the shanks pointed downward, the diameter of the tube being but slightly larger than that of the rivet heads. Near its lower end the tube, D, is transversely slotted at two points to permit the insertion of one or the other of the two wings of the escapement device, E; and, in the normal position of the parts the lowest rivet of the stack in the tube, D, is supported by the catch, E¹, (see Figs. 7 and 8).

The escapement device, E, is formed of sheet metal stock pivoted for oscillation 75 upon a pin, E³, and held yieldingly in the normal position above mentioned by means of a spring, E⁴, coiled about said pivot. The notched wing, E¹, is in the same plane with the portion of the device surrounding 80 the pivot, E³, while the other wing, E², is formed on an off-set portion, E⁵, and enters a slot in the tube, D, at a point slightly above the plane of the wing, E¹.

The material in which the rivet is to be 85 set having first been placed upon the clinching anvil, F, the driver, A, is caused to descend toward the anvil carrying with it the holder, G, mounted at its lower end. As shown in Figs. 3, 4 and 5, the holder, G, is 90 suspended on the end of the driver, A, by means of the mouthpiece, H, which is telescopically connected with the driver by means of the screw, H¹, engaging the slot, H², of the mouthpiece; by this means, when 95 the driver makes its descending stroke and the holder, G, comes into contact with the material on the anvil, F, and is supported thereby, the hammer rod, J, carried rigidly in the end of the driver, A, will descend 100 through the holder, G.

The descent of the driver, A, incidentally causes the depression of the push rod, K, whose upper end is provided with a yoke, K¹, embracing the driver, A, between a pair 105 of oppositely facing shoulders, A¹ and A², formed by cutting a notch in the cylindrical surface of the driver rod, A. The lower end

of the push rod, K, is beveled at K², to operate as a cam against the bent edge, E⁶, of the escapement member, E, thereby rotating the latter about its pivot, E³, and releasing the lowest rivet from the wing, E¹. The notch in the driver, A, however, is enough longer than the thickness of the yoke, K, to delay the movement of the push rod, K, until after the hammer rod, J, has descended 10 far enough to close the lower end of the delivery tube, D¹, as shown in Fig. 4; the rivet just released from the wing, E¹, is, therefore, not available for use in this stroke of the driver, A, but as the plunger, J, 15 re-cedes upward and passes the delivery opening of the tube, D¹, the rivet will drop into the hollow holder, G, in position to be driven by the next down stroke of the plunger J.

20 The purpose of timing the plunger stroke with respect to the escapement as above described is to cause the rivet to be delivered to the end of the tube, D¹, that is, where it debouches into the track of the plunger, J,— 25 as shown in Fig. 4, that is, leaning against the side of the plunger with its axis inclined. It will be seen that if the rivet delivered in the tubular chute, as seen in Fig. 4, found the end of the inclined portion, D¹, of the 30 chute opening without obstruction laterally into the mouth-piece, H; that is, if it arrived at that point before the plunger began to close the mouth, it would be liable to tip over and fall head-first, or head-edge- 35 wise, into the mouth-piece, and be encountered by the plunger in position inoperative for riveting; but arriving, as shown in Fig. 4, against the side of the plunger, and having opportunity of escape only as the plunger 40 rises, the lower end being released first while the head is still stopped against the side of the plunger, the rivet starts downward into the mouth-piece point foremost, as it should, and is well on its way into the 45 mouth-piece before the head is released; and when the head is released, it is too late for the rivet to tip over. It will be seen that this method of delivery permits the use of a tubular conduit for the rivet, distin- 50 guished from slotted track conduits which are frequently employed in machines of this general character.

The swing of the escapement, E, which released the lowest rivet from the ring, E¹, 55 will have caused the wing, E², to temporarily engage and support the next rivet of the stack, and the return of the escapement, E, to normal position during the upward movement of the driver, A, will have with- 60 drawn the wing, E², from under this second rivet, permitting the rivet to drop into control of the wing, E¹, in position to be re-leashed by the next down stroke of the driver.

65 The holder, G, is originally made from a single piece, its lower aperture, G¹, being

bored out to the size of the rivet shank; but, when the holder is medially sawed in two the waste resulting from the saw-cut is sufficient to reduce the width of the aperture, G¹, when the two parts are mounted in contact so as to prevent the shank of the rivet from depending from the holder until it is forced through the aperture, G¹, by the descent of the hammer rod, J. The two halves of the holder, G, are hinged upon the lower 70 end of the mouthpiece, H, so as to be swung apart by the descent of the hammer, J, as the latter engages their sloping interior walls, G², but the parts are normally held in contact by an elastic girdle of coiled 75 spring wire, G³. Thus if very accurate positioning of the rivet in the goods is required, the hammer rod, J, may be forced down only far enough to protrude the shank 80 of the rivet from the yielding jaws of the holder, G, and if it is then desired to shift the goods upon the anvil, F, a slight retraction of the hammer rod will permit the rivet to be forced back into the cavity of the holder, so as not to catch in the goods and 85 prevent shifting them upon the anvil; and the holder itself may even be lifted bodily off from the goods by reason of its loose connection at the slot, H², with the driver, A.

90 Preferably and in order to permit the machine to be used without the automatic feed device, if desired, the portion, D¹, of the feed tube D, is separate from the preceding portion of the tube and is permanently fixed in the mouthpiece, H, at the 95 lower end of the driver, A; the fitting, M, which is secured to the lower end of the removable portion of the tube, D, and serves for mounting the escapement device, E, has 100 formed integrally with it a clamp, M¹, adapted to engage the portion D¹, of the feed tube, for connecting the two portions of the tube. Thus by releasing the clamp screw, M², the upper portion of the tube together 105 with the escapement, E, may be entirely disconnected and moved out of operative relation 110 to the rest of the machine.

I claim:—

1. In a rivet setting machine, a hollow holder for rivets, a hammer rod mounted to 115 reciprocate through said hollow holder for driving a rivet therefrom, the cavity of said holder narrowing downwardly and the lower end thereof being made in parts mounted to separate laterally for releasing the rivet, the lower end portion of the holder being reduced in diameter at a short distance back of the end to form a neck, and an endless coiled spring forming an 120 elastic girdle lodged about said neck encircling said separable parts.

125 2. In a rivet setting machine, a driver mounted for reciprocation, a hammer rod on said driver, a hollow holder for the rivets telescopically hung on the end of the driver 130

inclosing said hammer rod, a rivet supply tube mounted to reciprocate with the holder and communicating laterally with the cavity thereof, and an escapement device controlling the rivets in said supply tube, arranged for actuation by the relative movement between the telescopically connected driver and holder, and adapted to feed one rivet to said holder at each reciprocation of the driver.

3. In a rivet setting machine, a hollow holder for rivets, a hammer rod mounted to reciprocate through said hollow holder for driving a rivet therefrom, the holder being adapted to support such rivet in position to be driven, a rivet feed tube opening into the cavity of the holder between the upper and lower limits of the hammer travel, and arranged to be closed by the hammer rod in its reciprocation, and means for controlling the rivets in said feed tube, arranged for actuation by said reciprocation of the hammer rod and adapted to release a rivet for delivery to the holder while the opening to said holder is closed by the hammer rod.

4. In a rivet setting machine, in combination with a feed tube and a vertical mouth-piece into which the feed tube opens laterally, and from which the mouth-piece extends upwardly, the diameter of the feed tube being approximately equal to that of the rivet heads, permitting the rivets to be stacked end on end therein; an escapement device for controlling the feed of the rivets toward the mouth-piece, comprising two connected wings separated longitudinally of the tube mounted for alternate oscillation into and out of the path of the rivet heads therein; a driver which is reciprocated in the mouth-piece past the opening of the feed tube thereinto, for driving the rivets there-through, and connections from the driver for operating the escapement device to move the lower wing out of the rivet path while the discharge of the feed tube into the mouth-piece is closed by the driver.

5. In a rivet setting machine, in combination with a feed tube and a vertical mouth-piece into which the feed tube opens laterally, and from which the mouth-piece extends upwardly, the portion of the feed tube through which the delivery is made into the mouth-piece being tubular of a diameter approximately that of the rivet heads; an escapement device controlling the feed of the rivets toward the mouth-piece, to cause them to be delivered toward the mouth-piece, one in each cycle of the feeding and riveting action; a driver which is reciprocated in the mouth-piece past the opening of the feed tube thereinto, for driving the rivets there-through, and connections from the driver for operating the escapement device for final release of the rivet during the driving stroke of the driver, and while the

latter is in a position closing the discharge mouth of the feed tube into the mouth-piece.

6. In a rivet setting machine, in combination with a feed tube and a vertical mouth-piece leading to a holder, and into which the feed tube opens laterally, and from which said feed tube extends upward obliquely; means for delivering the rivets one by one and separately down the oblique discharge portion of the feed tube toward the mouth-piece; a driver which reciprocates in the mouth-piece past the lateral discharge at the lower portion of its stroke, and means operated synchronously with said stroke of the driver to release a rivet for delivery thereof through said oblique portion of the tube while the said discharge opening is closed by the driver.

7. In a rivet setting machine, in combination with a feed tube, and a vertical mouth-piece into which the feed tube opens laterally, and from which it extends upward with its lower side at an incline; a plunger operating in the mouth-piece past the discharge of the feed tube thereinto, adapted at one position in its stroke to close said opening, and means for delivering the rivets one at each complete reciprocation of the driver into said portion of the feed tube leading to the mouth-piece, said means being timed to cause such delivery while the driver is closing the opening of said tube into the mouth piece.

8. In a rivet setting machine, in combination with a feed tube having a terminal portion extending obliquely downward, and a vertical mouth-piece into which it leads laterally; said tube being cylindrical and of diameter approximating that of the rivet heads; means for delivering the rivets point-foremost and lodged for sliding in said inclined portion of the tube for arriving one at a time at the entrance to the mouth-piece, and a plunger operating in the mouth-piece and adapted to close the opening of the tube thereinto, the means for delivering the rivets and for reciprocating the plunger being relatively timed to cause a rivet to be delivered while the plunger is in position for closing said entrance to the mouth-piece.

9. In a rivet setting machine, in combination with a feed tube in which the rivets are adapted to be stacked end on end, an escapement device for controlling the feed of the rivets through the tube, comprising a member mounted for oscillation on the tube, having two rivet-obstructing members extending in planes transverse of the tube, and at a distance apart along the path of the rivets therethrough, said members being positioned with relation to the axis of oscillation at an angle to each other whereby the oscillation of said escapement device to carry one member into said path, carries the other member

out of the path; means yieldingly holding said escapement device at one limit of its range of movement; a mouth-piece to which the rivets are delivered from the feed tube; 5 a driver operating in said mouth-piece and a cam member operatively connected with the driver and positioned for encountering said escapement device for oscillating it toward the opposite limit during the descent of the driver.

10. In a rivet setting machine, a driver mounted for reciprocation, a hammer rod on said driver, a hollow rivet holder telescopically hung on the end of the driver 15 inclosing said hammer rod, a rivet supply tube mounted to reciprocate with the holder and opening laterally into the cavity thereof,

an escapement device controlling the rivets in said supply tube, means for actuating said device, comprising a cam member, and co-operating abutments on said cam member and driver, respectively, said abutments being spaced apart at the upper limit of reciprocation of said driver sufficiently to delay the actuation of the escapement until the 20 opening of the feed tube is closed by the descent of the hammer rod into the holder. 25

In testimony whereof I have hereunto set my hand at Chicago, Illinois, this 17th of October, 1913.

DAVID C. SASSEMAN.
